By *Justin L Sargent*

Attorney

UNITED STATES PATENT OFFICE.

WILLIAM HENRY GARLOCK, OF SEATTLE, WASHINGTON.

SURGICAL APPARATUS.

Application filed December 8, 1921. Serial No. 521,010.

To all whom it may concern:

Be it known that I, WILLIAM H. GARLOCK, a citizen of the United States, residing at Seattle, in the county of King and State of Washington, have invented a new and useful 5 Surgical Apparatus, of which the following is a specification.

The object of my invention is to provide a new and improved device for supporting the 10 broken limb of a person in proper position while the bone is going through the process of reuniting; and to provide an apparatus which will replace and be more efficient than the plaster cast or the rigid splint formerly 15 used. It is an especial object of my invention to provide a device which will allow a change of the position of the affected limb so as to prevent stiffening of joints and 20 muscles that have not been injured. It is also an especial object of my invention to provide novel means for adjusting the device in a rotary direction relative to the limb so as to allow the ends of the broken bone to 25 be placed in exact position for reunion, and to provide a device which permits of the placing of suitable packing or padding between the frame and the broken limb. It is 30 also an object of my invention to provide means for longitudinal adjustment of the apparatus relative to the position of the patient. It is also an object to provide the 35 novel combination and arrangement of parts herein disclosed. I attain these and other objects of my invention by the mechanism illustrated in the accompanying drawings, in which:—

Figure 1 is a side elevation of the apparatus, showing it in use;

Fig. 2 is a detail top plan of a portion of 40 the apparatus;

Fig. 3 is a side elevation of member 25;

Fig. 4 is a top plan of same;

Fig. 5 is a side elevation of the main portion of the apparatus showing in dotted lines 45 how it may be adjusted;

Fig. 6 is a top plan of the cradle or limb supporting means;

Fig. 7 is a section on line 7—7 of Fig. 9;

Fig. 8 is a vertical section on line 8—8 50 of Fig. 5;

Fig. 9 is a top plan of member 3; and

Fig. 10 is a detail elevational view of members 8, 9 and 10.

Like numerals designate like parts in each 55 of the several views.

Referring to the accompanying drawings,

I provide suitable supports 2 carrying the frame members 1 extending longitudinally above the couch on which the patient reclines. I provide a padded ring 3 through 60 which the leg of the patient is inserted as shown in Fig. 1. This padded ring is provided with spaced arms 7, to which are attached the strands of a cord 4 which is run over the sheave 6 and attached to a weight 65 5. A second ring 8 is provided with suitable set screws 9 which engage the bone. Also attached to these set screws are suitable links 25 to which in turn are attached other ropes 4' which extend over sheaves 6' at the foot 70 of the couch or bed and are attached to a suitable weight 5'. The ring 8 is provided with a plurality of eyes 10 to which are attached bolt 11 that in turn are attached to eyes 12 secured to the main frame 1 as shown 75 in Fig. 1. Slidably mounted on the horizontal frame 1 I provide suitable adjustable slide members of clasps 22 secured in adjusted position by suitable set screws 23. From each member 22 depends a hanger 80 strap 20 having a buckle 21 by means of which it may be adjusted to the length desired. Straps 20 carry hooks 19 for detachably securing same to eyes 18, as shown in Fig. 8, of the semi-circular frame members 85 13 and 14. I provide an upper frame member 13 and a lower frame member 14 hinged to each other at 15 and reinforced by the semi-circular brace 24. Frame 13 carries the perforated semi-circular plate 16; and frame 14 carries the perforated semi-circular plate 17. I provide a link 25 to which the weight cords 4 extending to the foot of the couch are attached at 27. The end 26 of link 25 is mounted on the set screw 9, as shown 90 in Fig. 10.

In operation the padded ring 3 is slipped over the patient's leg to the crotch of the body. The ring 8 is applied to a suitable portion of the limb below the fractured portion; the flesh being slit and the pointed set screws set firmly on the bone. There being a plurality of eyes 10 spaced apart on the ring 8, it may be adjusted in a rotary direction to the extent desired. The 100 perforated plates 16 and 17 of the frames 13 and 14 respectively, support the upper and the lower portions of the leg of the patient. The hinge 15 permits of bending at the knee so that the muscles that are not injured will not suffer from lack of use while the bone is uniting. The shift of posi- 105 110

tion of the limb from time to time which this device permits prevents the stiffening of joints. The various hanger straps are independently adjustable. All parts however operate in conjunction to bring about the result of supporting the limb and stretching it at the same time. The stretching operation is essential to prevent the limb from becoming shorter after the bone has 10 become united.

What I claim is—

1. In a surgical apparatus of the class described, the combination of a frame disposed above the couch of the patient, means for supporting the upper portion of the injured limb, means for supporting the lower portion of the injured limb, hinged means hingedly connecting said upper and lower supporting means, adjustable means suspended from the frame member and by which the limb supporting means in turn are adjustably suspended, and means for securing said adjustable means in the desired adjusted position longitudinally of the frame member.

2. In a surgical apparatus of the class described, the combination of a frame disposed above the couch of the patient, independent means for supporting the lower portion of the injured limb, means hingedly connecting the aforesaid elements to permit of movement of the joint of the patient's injured limb, means for adjustably suspending the upper limb supporting means from the

frame, independent means for adjustably suspending the lower limb supporting means from the frame, means for adjustably securing the suspending elements on the frame, and a plurality of weighted means mounted on the patient's limb above and below the fractured portion for stretching same during convalescence.

3. As a new article of manufacture for an apparatus of the class described, the combination of a metal frame member, a semi-circular perforated plate secured to same, a second frame member, a semi-circular perforated metal plate secured to same, hinge means connecting said frames.

4. In an apparatus of the class described, the combination of a frame disposed above the couch of the patient, independent means for supporting the lower portion of the injured limb, means hingedly connecting the aforesaid elements to permit of movement of the joint of the patient's injured limb, means for adjustably suspending the upper limb supporting means from the frame, independent means for adjustably suspending the lower limb supporting means from the frame, means for adjustably securing the suspending elements on the frame, a plurality of weighted means mounted on the patient's limb above and below the fractured portion for stretching same during convalescence, and set screws in the hinge means adjustably engaging the bone.

WILLIAM HENRY GARLOCK.
